ATTORNEY

UNITED STATES PATENT OFFICE

MARTIN SALZMAN, OF BRONX, NEW YORK

STRAW HAT

Application filed December 31, 1930. Serial No. 505,687.

My invention relates to straw hats and the processes for making the same.

An object of my invention is to provide a highly improved and simplified process for manufacturing straw hats of the stiff straw type, requiring considerably less time and labor than processes now in use, and whereby straw hats made in accordance therewith will nevertheless be light, water-proof and durable in construction and attractive in appearance.

A further object of this invention is to provide a straw hat of the character described, which shall be comparatively inexpensive to manufacture, light and waterproof in construction and neat in appearance and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a transverse, diagrammatic cross-sectional view of a straw hat made in accordance with my invention;

Fig. 2 is a top plan view of my improved insert disposed between the upper portion of the brim and the under brim of the hat.

Referring now in detail to the drawings, 10 designates a straw hat embodying the invention here shown for the purpose of illustration, as a stiff straw hat made of ordinary flat foot braid. The hat comprises a woven straw crown 11 and a brim 12. Said brim is composed of an upper portion 13 and an under brim 14 sewed to each other as by stitching 15 adjacent the outer periphery of the brim. Interposed between the upper and lower portions 13 and 14 of the brim and sewed thereto by said stitching 15 is an elliptical ring shaped insert 16 made of

sheet material, slit as at 17 and gummed at both sides thereof, as at 18 and 19, for the purpose hereinafter described.

Said insert 16 may be made of paper, fabric, or any other suitable flexible or stiff sheet material. A sheet 20 gummed as at 21 at the upper side thereof may be attached to the underside of the top portion 22 of the crown for the purpose hereinafter set forth. The straw portions of the hat may be covered and saturated with lacquer or the like nitro-cellulose substance, as hereinafter described.

The process of making the hat 10 will now be described. The ordinary flat foot or the like straw braid which is soft, flexible and shapeless is first sewed together to form the crown and upper brim of the hat in the manner well known in the art. The insert 16 is then placed against the underside of the upper portion 13 of the brim with slit 17 at the rear portion of the brim, and the under brim 14 is then placed against the underside of the insert 16 and said parts 13, 16 and 14 are sewed together, as by stitching 15, adjacent the outer periphery of the brim. The hat is then steamed. During this steaming process, the gum or adhesive coatings 18 and 19 cause the insert 16 to adhere to the portions 13 and 14 of the brim. The steaming process will then cause strong attachment of the underbrim to the upper brim. Said insert furthermore serves to strengthen and give shape to the brim. The hat may then be pressed in a hydraulic press with a block, preferably one size smaller than the finished hat. This blocking operation in the hydraulic press is made possible at this stage of the process, because of the use of the insert 16 which gives sufficient shape to the brim to permit the hat to be blocked without first saturating the same with glue or the like adhesive substance, as has ordinarily been the practice heretofore. The elimination of this gluing operation makes for a saving of time, since ordinarily, the hat would first be dipped in glue and dried before hand blocking, said drying operation usually taking considerable time.

In accordance with my process, the hat, blocked as above described, is then dipped

into a lacquer solution suitably heavy enough to enable the same to stiffen the hat properly upon drying. Any suitable lacquer or nitro-cellulose solution may be used, preferably one 5 having an ester, gum or synthetic gum content. The lacquer dries in about four hours and becomes hard upon drying. Thus a relatively thin layer of lacquer is sufficient to give the hat the required stiffness. The lacquer, 10 furthermore, is water-proof and does not absorb moisture which would add to the weight of the hat.

The hat is then allowed to dry thoroughly 15 to permit the lacquer to harden, after which the hat is again pressed in the same hydraulic press as previously used, to render the same stiff. The hat may thereafter be sponged with alcohol and steamed so as to raise up 20 the braid which was flattened during the previous pressing operation. After sponging and steaming, the brim is preferably again pressed. Any weak spots may then be sprayed with lacquer.

Heretofore, in making hats of the general 25 type described, no insert was used and when the portions of the brim were sewed together, the hat was usually dipped in glue for stiffening the same and then allowed to dry, the drying process usually taking considerable 30 time. The hat was usually thereafter hand-blocked to give the same a rough shape and then allowed to dry again, said latter drying process taking further considerable time. The glued hats were thereafter steamed and 35 then blocked in a hydraulic press. In accordance with my invention, the hat is blocked before dipping in the lacquer. After blocking in the hydraulic press, the hat is dipped, allowed to dry and then again pressed 40 in a hydraulic press. Thus the hand blocking operation of the old process is eliminated and the time required for making the hat materially reduced. Lacquer has been found not to be sticky, is light and will not absorb 45 water, whereby the finished hat is as a whole much lighter and water-proof. Since the lacquer hardens considerably upon allowing the same to dry, only a thin film or coating of lacquer is necessary, whereby the hat may 50 be made lighter than heretofore. Furthermore, since the lacquer on the straw hat does not cause the hat to stick to the block, no powders need be used to prevent sticking of 55 the hat to the block, and the step of washing off powders is also eliminated.

It will thus be seen that there is provided a process and article in which the several objects of this invention are achieved, and which is well adapted to meet the conditions of practical use.

As various possible embodiments might be made of the above invention, and as various changes might be made in the embodiment above set forth, it is to be understood that all 65 matter herein set forth, or shown in the ac-

companying drawings is to be interpreted as illustrative and not in a limiting sense.

Having thus described my invention, I claim as new and desire to secure by Letters Patent:

1. A straw hat having a brim comprising upper and lower superimposed straw portions incorporated together by a paper sheet member, having adhesive on the opposite sides thereof, and interposed between said 70 brim portions.

2. A straw hat having a brim comprising upper and lower superimposed straw portions incorporated together by a paper sheet member, having adhesive on the opposite sides thereof, and interposed between said 80 brim portions.

3. A straw hat having a brim comprising upper and lower superimposed straw portions incorporated together by a sheet member, having adhesive on the opposite sides thereof, and interposed between said 85 brim portions, said brim having a waterproof coating.

4. A straw hat having a brim comprising 90 upper and lower superimposed straw portions incorporated together by a sheet member by means of adhesive applied to the opposite sides thereof, said sheet member being interposed between said brim portions.

5. A process of manufacturing a straw hat consisting in interposing a sheet member gummed on both sides, between upper and lower portions of the brim, steaming the hat 100 to cause the brim portions to be incorporated together by said interposed member, then blocking said hat and coating said hat in a lacquer solution.

6. A process of manufacturing a straw hat comprising superposing upper and lower 105 straw brim portions and an intervening sheet member having adhesive on both sides thereof, steaming the hat to cause the brim portions to be incorporated together by said intervening member, and then blocking the hat. 110

7. A process of manufacturing a straw hat comprising superposing upper and lower straw brim portions and an intervening sheet member having adhesive applied to the opposite sides thereof, causing the brim portions 115 to be incorporated together by said intervening sheet member and adhesive, then blocking said hat and coating said hat in a lacquer solution.

8. A process of manufacturing a straw hat comprising superposing upper and lower straw brim portions and an intervening sheet member having adhesive on both sides thereof, steaming the hat to cause the brim portions to be incorporated together by said intervening member, then blocking said hat and coating said hat in a waterproofing solution.

In testimony whereof I affix my signature.

MARTIN SALZMAN.
